Application May 3, 1941, Serial No. 391,676

3 Claims. (Cl. 179—171.5)

The present invention relates to modulated wave transmission and especially to a circuit for generating a carrier frequency wave and modulating the wave by signals such as speech.

A particular object is a self-oscillating modulator of simple construction with provision for suppressing the unmodulated carrier component.

Many well-known types of modulators depend upon some form of balance to suppress the carrier, such as a differential or bridge arrangement of tubes or impedances whereby the unmodulated carrier component appears across a circuit element that is in conjugate relation to the outgoing line.

One of the objects of the present invention is a carrier suppression modulator that depends upon a direct shunting of the carrier and that avoids the necessity of any bridge or differential arrangement.

The nature and objects of the invention will be more fully disclosed in the description to follow, and from the accompanying drawing in which:

Figs. 1 and 2 are schematic circuit sketches of illustrative embodiments and Fig. 3 shows impedance diagrams to be referred to in the description.

Fig. 1 shows a tube 1 with a crystal 2 which serves the dual purpose of determining the frequency of oscillation and shunting the unmodulated carrier from the load circuit.

The tube 1 has its control grid connected to the secondary winding of input speech coil 3, and thence through resistor 4 and condenser 5 in parallel, to the cathode. The anode is connected to output coil 6. The plate has a high frequency circuit to ground via plates 7, 8 of the crystal 2. Plates 8 and 9 are in the circuit of a second grid 10. The circuit oscillates by virtue of the coupling within the crystal between the circuit 7, 8 and the circuit 8, 9. The circuit oscillates at the series resonant frequency of the crystal. When speech is applied from the voice input circuit through coil 3 to the grid, the carrier waves are modulated by the action of the tube and the two side-bands are transmitted through output coil 6 to the line or load circuit 11 while the carrier is shunted through the circuit comprising crystal plates 7, 8.

The circuit as shown in Fig. 1 is provided with negative feedback for the voice waves in order to reduce distortion and improve stability of operation. A portion of the output side-band is brought back over conductor 12, through loss

network 13 to the plate 14 of the diode within the envelope of tube 1. Also, some carrier wave is supplied to the diode plate 14 from plate 9 of the crystal via resistors 15 and 16. Demodulated speech flows in the diode circuit in series with resistors 16 and 4, the carrier being bypassed through condenser 5. Resistor 4, being common to the grid circuit, puts the demodulated speech back on the grid in inverse phase with respect to the original speech. This results in a reduction of gain of the circuit with the usual accompanying advantages of negative feedback.

In Fig. 2, a generally similar circuit is shown with the circuit proportioning more fully set forth. The tube 20 has its control grid connected to speech input coil 3 and its anode connected to output coil 6 and crystal 2, similarly to Fig. 1. Feedback of the carrier for producing oscillations is through condenser 21 to the grid 22, which has a leak resistor 23 to ground. The cathode is above ground for direct current by the drop through bias resistor 24 which has the usual shunting condenser 25. The negative feedback path is from the plate through condenser 26 to the diode plate 14, this feedback being effective at the frequencies of the lower side-band and carrier by virtue of impedance network Z₃ as may be seen from Fig. 3 where Z₃ is indicated as having high impedance at these frequencies. The demodulated speech flows through the diode and networks Z₃ and Z₄ in series. Reference to Fig. 3 shows that Z₄ has high impedance over the voice range so that a feedback of the demodulated speech takes place into the grid circuit, the grid being connected to the upper or ungrounded terminal of the network Z₄.

The network Z₂ is designed to have a high impedance at the desired output frequencies, in this case the lower sideband and the carrier, and it assists in making the load impedance approximate an impedance match to the tube for the wanted frequencies. Looking to the right just beyond network Z₂, the impedance Z₁ is seen to be practically zero at the carrier frequency but high over the wanted side-band. This results in effective suppression of the unmodulated carrier component and transmission of the lower side-band into the outgoing circuit 11. Circuit 11 contains a band-pass filter 28 for passing the lower side-band and suppressing other frequencies.

A suitable configuration is given for each of the networks Z₂, Z₃ and Z₄. Z₃, for example,

comprises an inductive branch offering low series attenuation to low frequencies and a capacitive branch offering low series attenuation at high frequencies. At intermediate frequencies (see Fig. 3) the inductance and capacity tend to antiresonate but the resistive branch flattens out the resonance curve as shown.

In the case of network Z₄, the capacitive branch offers low impedance to the carrier and other high frequencies while the other branches give a shaped impedance over the voice band to provide the desired type of feedback.

In the case of network Z₂, the inductive branch gives low impedance to low frequencies, the capacity branch gives low impedance to high frequencies while the capacity in conjunction with the two other branches provides a major and a minor antiresonant effect suitably spaced and damped as indicated in Fig. 3. The exact dimensioning will, of course, differ with different frequencies, the configurations and impedances being illustrative and not limiting.

The circuit details may be varied widely in practice without departing from the invention. For example, while the coupling from plate 8 to the oscillator grid is shown as quite simple in character, it may be advantageous in practice to use other elements in this coupling circuit in order to secure desired phase shift in particular cases, or to provide for a voltage step-up. These and other modifications will occur to those skilled in the art. The scope of the invention is defined in the claims which follow.

What is claimed is:

1. In a carrier wave modulating circuit, a space discharge device having at least triode elements, a source of modulating waves and a transmission circuit, a piezoelectric crystal coupling electrodes of said device to cause the devices to produce oscillations of the carrier frequency, circuits coupling said source of modulating waves with electrodes of said device to produce modulation of said carrier frequency oscillations, con-

nections for impressing the modulated waves on said transmission circuit and for suppressing transmission of the unmodulated carrier component, said latter connections comprising a circuit including electrodes of said crystal in shunt across said transmission circuit to provide a substantial short circuit at the carrier frequency.

2. In a modulating circuit, a space discharge tube having at least triode elements, a crystal having a plurality of plates, a speech input circuit, an outgoing circuit for modulated waves, a coupling from plate to grid through said crystal causing said tube to generate oscillations of carrier frequency determined by said crystal, connections between said speech input circuit and said tube for producing modulation in said tube of said generated frequency oscillations by the speech, means to impress the modulated waves on said outgoing circuit, and a circuit including a pair of plates of said crystal for shunting the unmodulated carrier component from said outgoing circuit.

3. In combination, a space discharge device having cathode, grid and anode elements, a crystal, circuit means coupling said crystal in a resonant path between plate and grid elements of said device, said coupling means causing said device to generate sustained waves of a frequency determined by the crystal, means including a source of signal waves coupled to elements of said device to produce modulation of said waves, an outgoing circuit for the modulated waves coupled to plate and cathode elements of said device, and means for suppressing transmission to said outgoing circuit of the unmodulated component of the modulated waves, said latter means comprising a series resonant circuit including said crystal connected in shunt across said outgoing circuit.
